UNITED STATES PATENT OFFICE.

EZRA H. BALMFORTH, OF MEDFORD, MASSACHUSETTS, ASSIGNOR TO SAMUEL WARD MANUFACTURING COMPANY, OF BOSTON, MASSACHUSETTS, A CORPORATION OF MASSACHUSETTS.

COMBINATION CASE.

Application filed April 13, 1927. Serial No. 183,583.

For the greater convenience of the card player, various combination cases or sets adapted to contain in a unitary package both the decks of cards themselves and the necessary accessories of the game, as score pads, pencils, markers, counters, etc., have been devised.

My present invention relates to this general class of cases, but involves certain features of construction and arrangement whereby the decks of cards and the accessories of the game are not only compactly packaged but are capable of being most conveniently brought into use.

To this end, my case comprises a foldable cover or casing forming member, one fold section of which carries a card holder adapted to fold into and out of a compartment in an adjacent fold section of the cover member by and in the opening and closing movements of the cover member and when opened presenting the deck or decks of cards in a position adapted for convenient removal. The same opening movement of the cover member generally also brings into position a score pad and pencil mounted on the inner face of another fold section of the cover member, the arrangement being such that this section of the cover member serves as a writing foundation or backing for the pad when the case is open, and the pad folding down over the card holder when the case is closed.

As illustrative of my invention, I have shown in the accompanying drawings a form of case which I have found satisfactory in use and well adapted to the requirements of manufacture.

In the drawings:

Fig. 1 is a perspective view of a case in accordance with my invention and showing the case open.

Fig. 2 is an end elevation thereof showing the case partly closed.

Fig. 3 is a horizontal section showing the case completely closed.

Fig. 4 is a longitudinal section on the line 4-4 of Fig. 1 and particularly illustrating the mounting of the score pad.

I have indicated at A the cover or casing-forming member generally of my combination case. This member may be of cardboard or like material of sufficient strength and stiffness and may be covered with any

suitable material, as leather or fabric. The 55 cover member is shaped to provide, when folded along the indicated lines of fold 1, 2, 3 and 4, respectively, a top wall 5, a side wall 6, a bottom wall 7, a side wall 8, and a fastening flap 9 adapted to be overfolded 60 upon the top wall 5 and to be detachably fastened thereto, as by the interengaging ball and socket fasteners 10 and 11 mounted respectively on the outer face of the wall 5 65 and inner face of the flap 9.

When folded along the indicated lines of fold 1, 2, 3 and 4, the cover or casing-forming member A defines a generally rectangular, open-ended container, the ends and one side wall of which are closed and the structure generally stiffened by a compartment defining member B mounted on the inner face of the bottom wall 7. The member B is of generally rectangular form, presenting spaced end walls 12 and 13 and a connecting side wall 14 disposed at or about the fold line 3, the side wall opposite the wall 14 being omitted to permit a card holder, indicated generally at H, mounted on the inner face of the side wall 6 between the fold lines 1 and 2 to be folded into the compartment 15 thus provided by the member B.

The holder H is shaped to provide with the underlying portion of the wall 6 an 85 open-topped container within which one or more decks of playing cards C may be endwise inserted from above. As here shown, such holder comprises spaced end walls 17 and connecting side walls 18, and the enclosure thus defined is divided approximately midway between its ends as by the dividing block 19 to provide a pair of pockets 90 adapted each to accommodate a full deck 95 of cards.

The parts are so proportioned that when the filled holder H is swung down into its compartment 15, both it and the decks of cards clear the walls 12, 13 and 14 of the compartment-forming member B and are 100 received snugly within and protected by such walls, as shown in Fig. 3. When swung upwardly out of said compartment, the holder moves to the erected position shown in Fig. 1 and remains in such erected position until the case is again closed, thus presenting the cards at the most convenient position for withdrawal and use. 105

To the inner face of the top wall 1 of the cover member A, I secure such accessories as may be most desirable, depending upon the game being played. In the present embodiment, the case is intended for a bridge set and hence I provide with it a bridge score pad S and a pencil P. The score pad includes a tongue 20 of cardboard or the like adapted to be inserted into the upper 10 open end or the mouth of a pocket 21, formed in the inner face of the top wall 1, thereby permitting convenient replacement of the pad when necessary. Ordinarily the pad remains at all times within the pocket 15 and is moved into and out of writing position by and in the opening and closing movements of the top wall 1 of the case. When fully opened, as shown in Fig. 1, the case wall 1 serves as a backing and writing 20 foundation for the pad.

The pencil P is removably mounted on the top wall 1 adjacent the score pad by means of a simple loop 22 carried by the inner face of said wall.

From the foregoing, it will be seen that I provide a case in which the card holder is normally concealed within and covered and protected by the cover member when the case is closed and is automatically brought 30 into a position wherein the cards may be withdrawn therefrom by and in the opening movement of the case. This is also true of the score pad with the further feature of advantage that when the score card is exposed for use it need not be and is not intended to be removed from the case with consequent liability of forgetting to replace the pad when the game is finished.

It will also be noted that when the case is 40 closed, as shown in Fig. 3, the card holder, score pad and pencil all compactly store in the compartment 15 with the score pad overlying the card holder.

Various modifications in the construction 45 and arrangement of my combination case may obviously be resorted to without departing from the spirit of my invention, if within the limits of the appended claims.

What I therefore claim and desire to secure by Letters Patent is:

1. In a case of the class described, a casing-forming member adapted to be folded along spaced lines of fold to define when closed a substantially tubular enclosure, the 55 inner face of one of the fold sections having a compartment defining member closing the ends of the tubular enclosure defined by said casing-forming member when said cover member is folded upon itself, and a card holder mounted on the inner face of an adjacent fold section and adapted to fold into and out of said compartment by and in the opening and closing movements of the casing-forming member.

2. In a case of the class described, a

casing-forming member adapted to be folded along spaced lines of fold to define when closed a substantially tubular enclosure, the inner face of one of the fold sections having a compartment defining member closing the ends of the tubular enclosure defined by said casing-forming member when said member is folded upon itself, a score pad mounted on the inner face of the fold section of the casing-forming member opposite that section carrying the compartment-defining member, and a card holder mounted on the inner face of a fold section of the casing-forming member intermediate of said above-named sections, said card holder and pad folding into and out of said compartment by and in the opening and closing movements of the casing-forming member.

3. In a case of the class described, a 85 casing-forming member adapted to be folded along spaced lines of fold to define a substantially tubular enclosure, a score pad mounted on the inner face of one of said fold sections, the inner face of an opposite fold section having a compartment defining member presenting closures for the ends of said enclosure when the casing-forming member is folded upon itself, and a card holder mounted on a fold section intermediate of said above-named fold sections, said card holder and score pad folding into and out of said compartment defining member by and in the opening and closing movements of the casing-forming member generally and when folded into said compartment the score pad being superposed upon said card holder.

4. In a case of the class described, a casing-forming member adapted to be 105 folded along spaced lines of fold to define a substantially tubular enclosure, a score pad mounted on the inner face of one of said fold sections, a three sided compartment defining member presenting closures for the ends and one side of said enclosure when the casing-forming member is folded upon itself, and a card holder mounted on a fold section intermediate of said above-named fold sections, said card holder and score pad 110 folding into and out of said compartment defining member by and in the opening and closing movements of the casing-forming member generally and when folded into said compartment the score pad being superposed upon said card holder.

5. A case of the class described, comprising a casing-forming member foldable along spaced lines of fold to define when closed a substantially tubular enclosure presenting a top wall, a side wall, a bottom wall, a side wall and an overlapping closure flap, said top wall constructed on its inner face to receive play accessories, a card holder mounted on the inner face of said 120

side wall, the inner face of said bottom wall having a compartment defining member disposed in position to receive said card holder and accessories when the casing-forming member is folded to closed position, said compartment-defining member presenting end closure portions for the ends of the tubular enclosure and the opening and closing movements of said casing-forming member automatically carrying said

card holder and accessories into and out of said compartment-defining member, and interengageable means on said closure flap and top wall, respectively, of the casing-forming member for locking the case in closed position.

In testimony whereof I affix my signature.

EZRA H. BALMFORTH.
